UNITED STATES PATENT OFFICE.

JOHN M. THOMPSON AND WILLIAM H. THOMPSON, OF BUFFALO, NEW YORK.

DRAINPIPE PLUG.

Application filed October 20, 1920. Serial No. 418,175.

To all whom it may concern:

Be it known that we, JOHN M. THOMPSON and WILLIAM H. THOMPSON, citizens of the United States, residing at Buffalo, in 5 the county of Erie and State of New York, have invented a new and useful Improvement in Drainpipe Plugs, of which the following is a specification.

This invention relates to plugs or stoppers for drainpipes or the like, and more particularly to plugs or stoppers for drainpipes of the kind which are not provided with screw threads or other means to which a plug or stopper may be secured.

10 Most drainpipes which are now used for draining basements or cellars and which connect with sewers, are not provided with plugs, and consequently, if the water backs in the sewer, the cellar or basement may be come flooded. Sewer gases and odors also sometimes enter the cellar or basement through the drainpipes. When it is desired to provide the drainpipe with a plug, it is generally necessary to remove the upper section of the drainpipe and replace it by a corresponding section of pipe having a threaded upper end, which necessitates breaking through the cellar or basement floor and digging below the floor to remove 20 the section of pipe and insert the new section.

The objects of this invention are to provide a plug for drainpipes which can be readily applied to drainpipes of usual construction and which does not necessitate any change in the drainpipes; also to provide a plug of this kind which has a discharge passage which can be opened and closed without removing the plug from the drain pipe; also to provide means of improved construction for facilitating the insertion of the plug in a drainpipe, or the removal therefrom; also to improve the construction of devices of this kind in the other respects 30 hereinafter specified.

In the accompanying drawings:

Fig. 1 is a sectional view of a drainpipe showing in elevation a plug embodying the invention arranged in operative position in 35 the drainpipe.

Fig. 2 is a similar view showing the parts of the plug in a position in which the gasket is not expanded.

Fig. 3 is a central sectional elevation thereof on an enlarged scale showing the means used for expanding the gasket of the 40 plug.

Fig. 4 is a similar sectional elevation showing the plug in operative position in a pipe.

Fig. 5 is a top plan view of the plug showing the wrenches in operative relation thereto for expanding the gasket.

A represents the usual drainpipe which may be arranged in a cellar floor and a is the usual perforated cover therefor.

The drainpipe plug embodying the invention shown in the accompanying drawings includes two gasket-compressing members B and C which are adjustable relatively to each other, the upper member B being internally threaded as shown at b and the lower member C having an upper shank portion c externally threaded to engage with threads b. The upper member B preferably has an enlarged flange b' which prevents the upper part of the plug from entering into a drainpipe, and the lower member is preferably provided with an outwardly-extending flange c' engaging an 50 expandable gasket D, preferably made of rubber or other suitable material. E represents a spacing member or washer which is arranged between the expandable gasket D and the lower end of the upper gasket-compressing member B. When the upper and lower members B and C are turned relatively to each other the opposite faces of the gasket will be pressed toward each other, causing the gasket to expand as shown in 55 Figs. 1 and 4. The spacing member or washer E is preferably, though not necessarily used and serves to prevent the lower end of the member B from wearing or rubbing on the gasket D, and also eliminates 60 the friction which would result from having the lower end of the upper gasket-compressing member bear directly against the gasket.

The lower gasket-compressing member C 100

is preferably provided with a central hole or passage c^2 , which in the construction shown is square in cross section and is adapted to receive a key or wrench F of corresponding cross section. The upper compressing member B is also preferably provided with means adapted to cooperate with a wrench for turning these two members relatively to each other. In the construction shown for this purpose, the flange b' of the upper member B is provided with a pair of upwardly extending lugs G having apertures g into which the arms or projections g' of a wrench g^2 are adapted to enter. In the construction shown, one of the arms or projections of the wrench is considerably longer than the other, so that the wrench may easily be removed by first removing the short arm from engagement with the lug and then withdrawing the longer arm from its lug. A wrench of any other kind may be used in connection with the upper member B.

In inserting the device into a drainpipe, the plug is first placed into the position shown in Fig. 2. The wrenches F and g^2 are then placed into engagement with the lower and upper gasket-compressing members respectively and the wrench g^2 is turned in a direction to cause the compressing members to compress the gasket D to expand the same. As soon as the gasket engages the walls of the pipe A, the friction between the gasket and the walls makes it unnecessary to hold the wrench F, and the further expansion of the gasket D may be accomplished by turning the wrench g^2 only. By making the gasket of soft rubber or analogous material, the gasket will form a tight joint with the pipe A, regardless of irregularities or roughness on the walls of the pipe.

The central hole or passage c^2 , together with the upper tubular, compressing member B forms a passage through the drainpipe plug, through which water may be drained from the cellar or basement. When desired, this passage through the drainpipe plug may be closed by means of a screw plug 50 or closing device H adapted to engage the threaded portion b of the member B. This plug is preferably provided with a washer or gasket h. When the plug H is in place, the passage through the drainpipe plug is closed. By removing the screw plug H, water can be drained from a cellar or basement without the necessity of removing the drainpipe plug from the drainpipe.

The drainpipe plug described can be easily inserted in a drainpipe and when in place and closed by the screw plug H, prevents water from backing from a sewer through the drainpipe and flooding a cellar or basement. The plug also prevents sewer

gases or odors from escaping through the drainpipe. The plug can be inexpensively made and can be readily placed in operative position in a drainpipe and requires no changes in the drainpipe itself.

We claim as our invention:

1. In a pipe plug, the combination of a member having a tubular stem and an integral flange on one end thereof, a second tubular member into which a part of the stem of said first member is adapted to extend, an expansible gasket arranged between said flange and said second tubular member, means for drawing said parts toward each other to compress said gasket between said flange and said second tubular member for causing the gasket to engage the pipe, and means for closing the passage through said tubular members.

2. In a drainpipe plug, the combination of two relatively movable parts adapted to be inserted into a drainpipe, one of said parts having a flange which is of greater diameter than said drainpipe and having a threaded portion engaging with a correspondingly threaded portion of the other part, an expansible gasket adapted to be compressed by said two parts to press said gasket into engagement with a drainpipe, said other part having a socket adapted to receive a wrench and said flange having parts adapted to cooperate with another wrench whereby said two parts may be turned relatively to each other.

3. In a drainpipe plug, the combination of two tubular members, one of which is externally threaded and the other of which is internally threaded, an expansible gasket adapted to be compressed by said two members for causing said gasket to engage the drainpipe, and a screw plug adapted to engage with the internally threaded member for closing the passage through said two tubular members.

4. In a drainpipe plug, the combination of two tubular members, one of which is externally threaded and the other of which is internally threaded, said externally threaded member having an axial passage adapted to receive a wrench, an expansible gasket adapted to be compressed by said two members for causing said gasket to engage the drainpipe, to close said drainpipe to the passage of liquid except through said tubular members, means on said internally threaded member with which a wrench is adapted to engage for turning said members relatively to each other, and means engaging with said internally threaded member for closing the passage through said members.

5. In a pipe plug, the combination of two tubular members having a screw-threaded engagement with each other for adjusting said members relatively to each other, one of

said members having a part extending into said other member and provided on said part with means for engaging a wrench, an expandible gasket adapted when compressed to engage the pipe, means connected with said tubular members for compressing said gasket to expand the same when said mem-

bers are adjusted relatively to each other, and means for closing the passage through said members.

Witness our hands this 19th day of October, 1920.

JOHN M. THOMPSON.

WILLIAM H. THOMPSON.
